UNITED STATES PATENT OFFICE.

ALBERT W. MOYER, OF NEW YORK, N. Y.

FURNACE.

1,202,303.

Specification of Letters Patent.

Patented Oct. 24, 1916.

Application filed December 3, 1915. Serial No. 64,814.

To all whom it may concern:

Be it known that I, ALBERT W. MOYER, a citizen of the United States of America, residing at New York city, New York, have 5 invented a new and useful Furnace, of which the following is a specification.

My present invention relates particularly to "heat treating" furnaces for annealing, hardening, tempering and otherwise heat 10 treating different articles.

A special object of my invention is to secure substantially uniform and even heating of relatively large and bulky objects.

Other objects are to conserve and prevent 15 loss or waste of heat and to effectively control the heat.

These objects I have attained by constructing my furnace with a heating chamber, a combustion chamber above the heating chamber and separated from the heating chamber by a substantially horizontal imperforate wall, and by conducting the heat from the combustion chamber downwardly around the separating wall and into the heating chamber beneath said imperforate wall. The waste heat is led off from the heating chamber through exhaust flues and the flow of heat through the heating chamber is so governed as to produce practically uniform heating effect throughout the chamber. In a preferred construction the heat conducting flues open into the heating chamber at different elevations, and the flues are proportioned in size according to 30 their distance from the source of heat. The heat is preferably supplied by burners discharging into the opposite sides of the combustion chamber, and the various flues are preferably formed as passages in the side 40 walls of the furnace body.

Various other features and the details of construction, will appear as the specification proceeds.

In the accompanying drawings, I have 45 illustrated my invention embodied in a preferred form and in a slightly modified form, but it will be understood that other changes and modifications may be made without departing from the true spirit and scope of 50 the invention.

In the drawings: Figure 1 is a transverse sectional view of a car type or movable hearth furnace embodying my invention. Fig. 2 is a longitudinal sectional view of the same. Fig. 55 3 is a transverse sectional view similar to Fig. 1 of a slightly modified form of the

invention. Fig. 4 is a longitudinal sectional view of the second form.

In the illustration, the combustion chamber is designated 7, and the heating or treating chamber is designated 8, the combustion chamber being located above the heating chamber and separated therefrom by a substantially horizontally disposed imperforate wall 9. The furnace is usually constructed 60 with side walls 10 connected at the top by a top wall 11, which forms the roof to the combustion chamber, and the imperforate defining wall 9 is preferably in the 65 form of an arch connecting the two side walls, as indicated. The heating chamber is made relatively high to accommodate tall or bulky pieces of work, such as boxes of articles to be annealed, sheet metal, and the like. The heat is preferably supplied by 70 gas or oil burners, such as those indicated at 15, discharging in through openings 16 in the side walls into opposite sides of the combustion chamber. The heat products are 75 conducted from the combustion chamber around the imperforate separating wall and into the heating chamber by flues consisting in the illustration, of vertical passages 17 formed in the side walls communicating at 80 their upper ends by lateral passages 18 with the combustion chamber, and at the lower ends by lateral passages 19 with the heating chamber. In the first form of the invention illustrated, a plurality of these 85 branch passages 19 opening into the heating chamber are provided for each vertical heat conducting flue 17, and the cross sectional area of the branch passages is proportioned 90 according to the distance of such passages from the source of heat. Thus, as illustrated, the branch passage 19 nearest the combustion chamber is made relatively small, and the passages farther away are made gradually larger. In this way a 95 substantially uniform flow of heat through the several passages is assured. The heat is 100 preferably introduced into the heating chamber at both sides thereof, the inlet passages at the opposite sides being preferably arranged in alternating relation, as indicated in Fig. 1, where the black arrows indicate the flow of heat entering at the left, and the dotted line arrows indicate the heat 105 entering from the inlets at the right, which, as indicated by the dotted lines, lie in a plane beyond that of the inlets at the left. Where, as in the illustration, burners are

provided discharging into the opposite sides of the combustion chamber, the burners at opposite sides are offset from each other so that the flow of one burner will not oppose the flow of the burner at the opposite side, and furthermore, the entrances 18 to the heat conducting flues 17, are preferably each located substantially opposite the burner at the opposite side, as shown in Fig. 1. Baffles 20 are preferably provided opposite the burner openings to break up the blast from the burner, thereby insuring proper combustion, and to deflect the flame somewhat so as to prevent its passage straight across the combustion chamber and out before combustion can take place. From the heating chamber the waste products are led off through exit or outlet flues consisting in the present disclosure of 20 downwardly extending passages 22 formed in the side walls communicating at the bottom with outlet conduits 23 leading to a stack 24 at the back of the furnace. In the form of the invention illustrated in Figs. 1 and 2, these outlet flues extend from the bottom of the heating chamber, communicating with the lower portion of the heating chamber by lateral passages 25.

In the form of my invention illustrated in Figs. 3 and 4, instead of entering the heat into the heating chamber at different levels, the heat is all entered at the bottom of the chamber, and passes out of the chamber through exits provided in the top of the chamber. Here the downwardly extending heat conducting passages 17' each have an outlet 19' opening into the bottom portion of the heating chamber, and the waste products escape from the upper portion of the heating chamber through outlets 27 opening into downwardly extending flues 22' leading to the outlet conduits 23'. This construction also forces the heat to traverse the entire heating chamber so as to heat it substantially uniformly throughout, and the crossfire of inflowing heat streams, as indicated by the arrows, prevents the formation of any pockets or dead areas.

The degree of heat is governed by means of the burners, and valves may be provided for controlling the flow of heat. Thus, in the illustration valves are shown at 30 for controlling flow through the exit flues. A further control may be exercised by means of a relief damper 31 in the exhaust stack 24. Opening this check damper reduces the draw of the stack on the outlet flues and so checks the outflow of the heat products.

To prevent loss of heat by radiation, the furnace walls are preferably covered with an external layer 33 of thermal insulating material. I find porous insulating brick to be an excellent material for this purpose.

The furnaces illustrated are of the car-bottom type, but it will be clear that the in-

vention is equally well adapted to a furnace of the stationary hearth type. The hearth, which in this case is in the form of a platform mounted on a car truck is designated 35, and the car truck which mounts it is 70 designated 36.

The furnaces shown are of single ended construction, having a door 38 only at one end, the opposite end being in the form of a solid wall 39. To prevent loss of heat around the edges of the door I preferably provide a seal in the form of a rearwardly extending down-turned flange 40 on the upper edge of the door which dips into a sealing groove 41 on the front of the furnace 80 over the door-way therein, and a dependent flange 42 on the lower edge of the door engaging in a sealing pocket provided by the channel or angle iron 43 on the outer end of the car. These sealing grooves or 85 channels support a suitable sealing medium, such as sand or the like. In the car-bottom type of furnace the edges of the car-bottom are preferably sealed by providing sealing channels 44 along the sides of the car into 90 which flanges 45 at the sides of the furnace dip, and a sealing channel 46 on the forward or innermost end of the car over which engages a shelf 47 on the rear wall 39 of the furnace.

95

From the foregoing it will be seen that the exceptional height given to the heating chamber adapts the furnace to the treatment of relatively tall and large objects, and the distribution of the heat through the heating chamber in the manner illustrated, produces a substantially even heating throughout such objects. The imperforate division wall between the combustion chamber and heating chamber in addition to its separating function, performs the additional function of transmitting heat to the heating chamber by radiation.

What I claim is:

1. An over fired heat treating furnace 11 comprising a furnace body having side walls connected by a top wall, a substantially horizontal imperforate wall extending across between the side walls and separating the interior of the furnace body into an upper 11 combustion chamber and a lower heating chamber, heat conducting flues extending from the combustion chamber down through one of the side walls and into the heating chamber beneath the imperforate separating 12 wall, exit flues leading out from the heating chamber for carrying away the waste products, and a burner discharging into the combustion chamber.

2. An over fired heat treating furnace 12 comprising a furnace body having side walls connected by a top wall, a substantially horizontal imperforate wall extending across between said side walls 13 and separating the interior of the furnace

- body into an upper combustion chamber and a lower heating chamber, said side walls having passages formed therein extending from the combustion chamber downwardly and 5 inwardly into the heating chamber at points below the imperforate separating wall, said side walls further having exit passages formed therein communicating with the heating chamber.
- 10 3. An over fired heat treating furnace comprising a furnace body having a heating chamber and a combustion chamber above said heating chamber, a substantially horizontal imperforate wall separating the heating chamber from the combustion chamber, a burner discharging into the combustion chamber and heat conducting flues in communication with the combustion chamber extending into the heating chamber at points 15 beneath the imperforate separating wall, said flues varying in cross sectional area according to the distance away from the source of heat to thereby equalize the flow of heat into the different portions of the heating chamber.
- 15 4. In combination, a furnace body having a heating chamber therein and a combustion chamber above said heating chamber, a substantially horizontal imperforate wall separating the heating chamber from the combustion chamber, a burner discharging into one side of the combustion chamber, a heat conducting flue extending from the opposite side of the combustion chamber substantially 20 opposite the point of discharge of the burner into the chamber, said heat conducting flue extending downwardly and into the heating chamber below the imperforate separating wall, and an outlet flue extending from the heating chamber in a plane substantially 25
- opposite the plane of entry of the heat conducting flue thereinto.
5. In combination, a furnace body having a heating chamber therein and a combustion chamber above said heating chamber, a substantially horizontal imperforate wall separating the heating chamber from the combustion chamber, a burner discharging into the combustion chamber, a heat conducting flue communicating at its upper end with the combustion chamber and extending downwardly below the imperforate separating wall, said flue having a plurality of inlets 30 opening at different levels into the heating chamber below the imperforate wall, the inlets at the higher levels being smaller than those at the lower levels to thereby substantially equalize the flow of heat into the heating chamber and exit flues leading off from the heating chamber. 35
6. An over fired heat treating furnace comprising a furnace body having a relatively high heating chamber to receive tall objects and a combustion chamber above said heating chamber, burners discharging into the combustion chamber, a substantially horizontal imperforate wall separating the heating chamber from the combustion chamber, and imparting heat to the upper portions 40 of objects in the heating chamber wholly by radiation, heat conducting flues extending from the combustion chamber around the imperforate separating wall and into the heating chamber beneath said wall, and exit flues extending from planes in the 45 heating chamber substantially opposite the planes of entry of the heat conducting flues thereinto to thereby compel a flow of heat throughout the heating chamber. 50

ALBERT W. MOYER.
